UNITED STATES PATENT OFFICE.

JOHN J. DUFFIE, OF NEW YORK, N. Y.

CERTIFICATION-CHECK WRITER.

Application filed September 24, 1924. Serial No. 739,740.

To all whom it may concern:

Be it known that I, JOHN J. DUFFIE, a citizen of the United States, residing at New York, in the county of New York and **5** State of New York, have invented certain new and useful Improvements in Certification-Check Writers, of which the following is a specification.

This invention relates to check protectors, **10** particularly to a device for protecting the certification of checks.

There have been many instances where the amounts for which certified checks are drawn have been raised, and the present invention **15** provides a device which prevents the raising of such checks by cutting into the paper on which the check is written a limiting amount which becomes a part of the certification of the check.

20 In the preferred embodiment of the invention, illustrated in the present application, the device operates in two stages, in one of which it prints the certification legend, including the date of certification, and **25** a serial number. In the other stage it prints a limiting amount in a space left blank for the purpose within the limits of the certification legend and preferably renders this limiting amount indelible by cutting it into **30** the paper of the check and saturating the incisions with ink.

The invention is susceptible of various embodiments falling within the scope of my claims, but the best form now known to me **35** is set forth in the accompanying drawings, in which:

Fig. 1 is a left side view of the machine showing the printing drum in elevated or retracted position and adjusted to present **40** the type face which prints the certification legend. In this view certain portions of the casing are broken away to show the internal construction and certain other details are indicated in dotted lines.

Fig. 2 is a view similar to Fig. 1, showing the type face for printing the certification legend lowered into contact with the platen. In this view the casing is almost entirely **45** broken away.

Fig. 3 is a vertical section through the complete machine on the axis of the printing drum.

Fig. 4 is a plan view of the complete machine with the cover broken away to expose **50** the internal mechanism.

Fig. 5 is a perspective view of the platen mechanism.

Fig. 6 is a detailed view of a full stroke mechanism.

Fig. 7 is a fragmentary view looking in **55** the direction of the arrow numbered 7 in Fig. 3 and illustrating how the type faces are guided to printing position.

Fig. 8 is a view of the printing drum and its connected indicating dial and actuating **60** wheel. In this view the type faces for printing the certification legend are illustrated.

The machine is supported on a base frame **65** 11 provided with feet 12 of rubber or the like and carrying a top plate or work support 13. Formed integrally with the base frame 11 is a hood or housing 14 in which the printing drum and other mechanisms are mounted.

This housing overhangs the work rest or **70** top plate 13 and is spaced therefrom a short distance, except at the extreme rear of the machine, to permit the insertion of the check or other slip to be printed upon.

Mounted beneath the work support 13 is a **75** yoke 15 which carries the platen. This yoke 15 is connected by screws 16 to the rear portion of the base frame 11 and it is similarly connected by two screws 17 to a web 18 formed integrally with the frame 11 near **80**

the front thereof. Mounted between the screws 17 and threaded into the yoke 15 are a pair of thrust screws 19 which bear at their ends at the web 18. The screws 17 and 19 act in opposition to each other. Thus **85** 90 it is possible to adjust the vertical position of the yoke 15 relatively to the work supporting plate 13. The use of the opposed sets of screws permits the yoke to be locked in position and the use of two sets, one at **95** each corner of the yoke, permits individual adjustment of the opposite sides of the platen.

This platen or printing surface is exposed by an opening in plate 13 and comprises a **100** layer of suitable resilient material 20 affixed to the upper surface of the yoke 15 and in position to receive the type faces herein-after described, which print the certification legend. Since the limiting amount is **105** printed in the middle of the certification legend and is cut into the paper the middle of the platen is cut away to receive the ser-rating platen bar which coacts with the limiting amount dies. For this reason yoke **110**

15 and the platen surface 20 carried thereby are provided with a transverse slot or recess in which is mounted the serrated platen bar 21. The platen bar 21 is vertically adjustable by means of opposed screws similar to those used to adjust the yoke 15. As shown in Figs. 1 and 3 the platen bar 21 is held in the groove by a pair of screws 22 which pass through the yoke 15 and are threaded into the bar 21 near its ends. Near the screws 22 are opposed screws 23 which are threaded into the yoke 15 and bear at their ends on the under side of the platen bar 21. Thus either end of the serrated platen bar 21 may be adjusted vertically by means of the screws 22 and 23, and when adjusted will be locked firmly in position. The top surface of the platen bar 21 normally stands below the top surface of the platen 20.

Journalized in the housing 14 is a cross shaft 24 which carries two forward extending arms 25 tied together by a yoke 26 so that they move as a single piece. Carried by the forward ends of the arms 25 is a hold-down plate 27 which is relatively narrow so as to overlie only a small portion of the platen surface 20 and which is provided with a longitudinal slot 28 which exposes the serrated plate 21. The hold down plate 27 is normally urged downward by a spring 29 which is connected to the rearwardly extending lever 30, and to a pin 31 on housing 14. A finger lever 32 fixed on the end of the shaft 24 offers means for manually lifting the hold down plate 27 to permit insertion or removal of the check.

The structure just described provides a large platen surface 20 to support the check while it receives the certification impression. The hold down plate 27 retains the check by pressing it into engagement with the platen along lines spaced from each other across the middle of the platen surface 45 adjacent the serrated platen bar. Besides retaining the check in position during the certification impression, it also retains the check during the printing of the limiting amount and strips the check from the cutting and printing die as the latter retreats from the printing position.

Journalized in the two side members of the housing 14 are a pair of hub members 35 and 36 which are connected together by a yoke or bail 37 rigidly connected thereto. This bail is provided to cause the hubs to move in unison and it is so dimensioned as to clear the printing drum hereinafter described, and to permit independent movements of the drum and of the hubs 35 and 36. The hubs 35 and 36 turn on ball bearings 38 which run on the margin of openings in the housing 14. The balls are retained in races formed in the hubs 35 and 65 36 to receive them by means of retaining

plates 39 and 40 which are connected with the hubs 35 and 36 by screws. Certain of these screws appear in dotted lines in Fig. 3.

In order to rotate the hubs 35 and 37 a crank arm 41 provided with a handle 42 is fixed to the hub 36. Its motion is limited to something less than 180° by limit stops. In order to retain the crank 41 in its normal or upward position a clock spring 43 is provided. This spring is connected at 75 one end to the hub 36 by inserting its in-turned end into a slot as shown at 44 in Figs. 2 and 3, and is connected at its opposite end to a stud 45 (see Fig. 2) carried by the housing 14.

The actuation of the handle 42 rotates the hubs 36 and brings the printing drum into engagement with the platen, the printing drum being mounted eccentrically in the hubs 35 and 36 as hereinafter described. 85 The printing drum carries as a part of the printing face an automatic numbering device which is advanced to the next number as the handle 42 returns to normal position. To prevent derangement of the number sequence it is desirable to provide a full stroke mechanism which will insure the complete movement of the handle 42 to the limit of its downward throw before permitting its return or upward movement.

Any full stroke device might be used, but I show and prefer a simple spring held pawl 46 which has a tooth 47 and which is pivoted at 48 on the inside of the housing 14. The pawl 46 is so positioned as to be in the path of the bail 37 and this bail is provided with teeth 49 with which the tooth 47 successively engages after the pawl is wiped up by the upward movement of the bail. When the handle 42 is moved downward the bail 37 swings upward and it engages the pawl 47 and moves beneath it, such engagement occurring prior to the time at which the counter mechanism is affected. As soon as engagement occurs between the pawl 46 and the bail 37 reverse movement of the bail is prevented until the bail shall have been moved to its extreme limit of travel, at which point it overruns the pawl 46 and permits the latter to swing to its normal position. When this has occurred, the bail 37 may swing back to its normal position, since it engages the smooth back of the pawl 46 and wipes the pawl out of its path.

A shaft 50 is mounted in the hubs 35 and 36 in eccentric relation thereto and so as to be rotatable therein. Fixed on the shaft 50 by means of a sleeve 51 is the printing drum 52, which is cylindrical in form except that at one point it carries a flat printing surface 53 tangent to the periphery of the drum and hence protruding at its margin beyond the circular contour thereof. This printing surface is provided with type or dies to print upon the check the desired certification

or other legend. These include two changeable printing devices, one of which prints the date of certification and the other of which prints the serial number of certification. These changeable printing devices may assume a number of known forms, but I show and prefer for the dating stamp a plurality of manually set type rings 54 mounted on a common axis and capable of being individually set to print the month, day and year.

For the numbering devices I make use of a known type of automatic numbering mechanism consisting of a plurality of type rings 55, the units ring being advanced step by step, one digit at a time, by motion of ratchet feed arm 56 (see Figs. 1 and 2) and the other rings of higher orders being actuated by successive transfer or carrying mechanisms. Numbering stamps, including such type rings, ratchet feed arms and carrying mechanisms, are standard articles of commerce and hence I deem it unnecessary to illustrate this mechanism in detail. Accordingly, I include in my drawings merely the type rings and the ratchet feed arm 56 which imparts step-by-step motion to the units ring.

The cylindrical portion of the printing drum 52 is provided with a series of spaced longitudinal dies 57, each of which prints in words a characteristic limiting amount, as, for example, "Eight hundred dollars". The various amounts printed by the successive dies may be chosen according to the needs of the user. But it may be stated generally that this feature is similar in its general aspects to that type of check writer which prints a limiting amount somewhat higher than the actual amount of the check rather than printing the exact amount of the check.

The drum, at its left end as viewed in Fig. 3, is provided with an impositive device consisting of a spring arm 60 having a roller 61 at its end, the roller 61 engaging a series of shallow notches 62 formed in the end of the drum 52. The arm 60 is journaled on the shaft 50 and, projecting below that shaft, is guided at its lower end by vertical slot 63 formed in the wall of housing 14. The point of engagement of the arm 60 with the slot 63 is closely adjacent that die 57, on the drum 52, which is in printing position. Accordingly, although the drum 52 moves transversely to its axis when it is moved to printing position by the actuation of handle 42, the detent is so guided by the slot 63 that the die is accurately presented.

It will be observed from a consideration of the eccentric mount of the shaft 50 in the hubs 35 and 36 that the drum 52 has a slight rolling movement as it engages the platen. Since the detent roller 61 is positioned by

engagement with the vertical slot 63 adjacent the printing point, the detent roller 61 acts to insure accurate presentation of the die. The same effect is secured for the indicating pointer 64 which also is journaled on the shaft 50 and is so connected to the detent arm 60 as to be guided by the slot 63. This pointer 64 coacts with a dial 65 fast on the shaft 50. The dial 65 bears legends, one of which indicates that the certification stamp is positioned at the printing point and the remainder of which give similar indications with reference to the amount-limiting dies. A knurled knob or handle 66 is the means by which the shaft 50 is rotated to bring the various dies to position.

It is desirable that the user be compelled to turn the printing drum in one direction only, for in this way complete inking of the drum by the inking rollers, hereinafter described, will be insured. On the other hand, it is desirable to permit a moderate range of reverse movement so that if the operator overruns the proper indication on the dial he can turn back to it. I accomplish the desired result by mounting on the shaft 50 a ratchet wheel 68. With this there coacts a pawl 69 mounted on a stud 70 on housing 14. Instead of providing a circular bearing in the pawl 69 to receive the stud 70, I provide the pawl with a longitudinal slot 71 (see Fig. 1) and draw it into engagement with the ratchet 68 by means of a spring 72 which performs the additional function of sliding the pawl forward on the stud 70 to the limit of motion permitted by the slot 71. If the user overruns the desired designation he may turn the dial backwards an amount limited by the length of the slot 71, and no farther. This insures that in the ordinary manipulation of the device the printing drum will be turned in one direction and yet permits slight reverse movement on occasion.

Although the detent roller 61 tends to position the printing drum, it is important to lock the drum positively once its motion towards printing position has commenced. This is effected by means of a lug or blade 73 which enters notches 74 in the right hand end of the drum 52. Since it is desirable for mechanical reasons to place the guide 73 to one side of the shaft 50 instead of directly below it, the notches 74 are on lines secant to the periphery of the drum rather than on radial lines. This will be readily understood from an inspection of Fig. 7.

In order to actuate the counter mechanism after each actuation of the certifying stamps, I provide a hook-like latch 76 which is pivoted on a stud 77 fast to the housing 14 and which is urged in engaging direction by means of a spring 78 coiled around the stud 77. The normal position of the latch 76 is shown in Fig. 1. When the

drum 52 is so positioned as to present the certification printing face to the platen, the latch 76 is in the path of downward movement of the lug 79 carried by the actuating 5 arm 56 of the counter mechanism. As the printing drum moves downward to printing position the lug 79 wipes back the latch 76 and just at the completion of the downward movement of the drum the latch snaps 10 over the lug 79 to the position shown in Fig. 2. When the drum swings backward to normal position it moves both forward and upward, the latch 76 therefore draws the arm 56 forward and down and the effect of 15 their conjoint movement is such that just as the arm 56 reaches its limit of downward movement it has so far overrun the nose of latch 76 that it suddenly cams back this latch and escapes therefrom. Upon its escape 20 the arm 56 is restored to its normal position by a retracting spring forming a part of the counter mechanism, and is therefore ready to repeat this cycle of operation.

It will be observed that the lug 79 cannot 25 engage the latch 76 when the amount-limiting dies are pressed to the platen. Consequently, the counter is actuated only after the actuation of the certification printing dies. Since the guide blade 73 pre- 30 cludes rotation of the drum 52 when the drum has been lowered very slightly from its normal position, there is no possibility of actuating the counter by the rotation of the drum.

In order to ink the drum I make use of 35 a roller 81 which is carried on a pivoted bracket 82 and is urged into contact with the periphery of the drum by a spring 83. The arm 82 is pivoted at 84 to the housing 40 14. The balance of the inking mechanism is mounted in a removable cover 85 which rests on top of the housing 14 and which is retained thereon by a strip 86 engaging a fixed stud 87 and by a spring 45 latch 88 engaging a latch stud 89. Ink is fed to the roller 81 at each actuation of the machine by means of a reservoir 90 whose forward end consists of an absorbent pad 92. The rear end of the reservoir 50 90 is sustained by a coil spring 93. The forward end is sustained by a pair of arms 94 fast on a shaft 95 journaled in the cover 85. This shaft is held in its normal position by a coil spring 96 and in such 55 normal position the reservoir 90 is retracted as shown in Fig. 1. The shaft 95 carries an arm 97 which is in the path of the bail 37 and as this bail approaches its limit of movement it engages the arm 97, drawing the reservoir 90 downward and forward and bringing the soaked pad 97 into contact with the roller 81. The reservoir 90 is kept filled with ink which is supplied through 60 the pad 97 to the roller and consequently with each actuation of the machine ink is 65

supplied from the pad 92 to the roll 81. A filling opening closed by hinged cap 98 permits the reservoir 90 to be replenished from time to time.

What is claimed is:

1. In a check certification machine, the combination of two printing instrumentalities, one arranged to print a certification legend and the second arranged to print a limiting amount in close association with 70 said legend, and actuating means common to the two printing instrumentalities and operable to actuate said printing instrumentalities successively.

2. In a check certification machine, the combination of two printing instrumentalities, one arranged to print a certification legend, and the second arranged to incise a limiting amount in close association with 75 said legend, and actuating means common to the two printing instrumentalities and operable to actuate said printing instrumentalities successively.

3. In a check certification machine, the combination of two printing instrumentalities, one arranged to print a certification legend, and the second arranged to print any selected one of various limiting amounts in close association with said legend; positioning means common to both said printing instrumentalities arranged to bring them to printing position successively; and a single actuating means operable to make an impression from whichever printing instrumentality is in printing position.

4. In a check certification machine, the combination of two printing instrumentalities, one arranged to print a certification legend and the second arranged to print a limiting amount in close association with such legend; an automatic numbering device associated with the first printing instrumentality and arranged to print a serial number as a part of said certification 100 legend; actuating means common to the two printing instrumentalities, operable to actuate said printing instrumentalities successively; and advancing means operable by the movements of said first printing instrumentality in making an impression, and arranged to advance said numbering device.

5. In a check certification machine, the combination of two printing instrumentalities, one arranged to print a certification legend and the second arranged to print any selected one of various limiting amounts in close association with said legend; an automatic numbering device arranged to print a serial number as a part of said certification 105 legend, positioning means common to both said printing instrumentalities arranged to bring them to printing position selectively; a single actuating means operable to make an impression from whichever printing instrumentality is in printing 110

position; and means for advancing said automatic numbering device arranged to be actuated by said actuating means when the first named printing instrumentality is in 5 printing position.

6. In a check certification machine, the combination of means for printing a certification legend, said means including an automatic numbering device for printing a 10 serial number as a part of the certification legend; means for printing a limiting amount in association with said certification legend; and means for advancing said numbering device by the printing movements 15 of the first named printing means.

7. In a check certification machine, the combination of two printing instrumentalities, one arranged to print a certification legend and the second arranged to print a 20 limiting amount in close association therewith; an automatic numbering device arranged to print a serial number as a part of said certification legend; means for advancing said numbering device arranged to be 25 operated by the printing movement of said numbering device; actuating means common to the two printing instrumentalities and operable to actuate said printing instrumentalities successively; and a full stroke device 30 controlling the movements of said actuating means.

8. In a check certification machine, the combination of means for printing a certification legend upon a check; an automatic 35 numbering device operable to print a serial number as a part of said certification legend; means for advancing said numbering device operable by the printing movements of said printing means; and a full stroke device 40 controlling the movements of said printing means.

9. In a check certification machine, the combination of a printing drum provided 45 with a printing face for printing a certification legend and with a plurality of printing faces for printing limiting amounts; an automatic numbering device carried by said drum and arranged to print a serial number as a part of said certification legend; means 50 for rotating said drum to present the various printing faces at the printing position; means for shifting said drum to print an impression of any printing face die so presented; and actuating means for said automatic numbering device arranged to be operated by said actuating means when, and 55 only when, said numbering device is in printing position.

10. The combination with a check protect-

ing device including a rotatable type carrying printing drum, and inking means therefor, of a ratchet mechanism arranged to oppose backward rotation of said drum while permitting unlimited forward motion; and yielding means associated with said 60 ratchet mechanism arranged to permit limited backward rotation of said drum.

11. The combination with a check protector, including a printing drum and inking means therefor, of a ratchet fixed to the 70 drum, and a yielding pawl engaging said ratchet and arranged to permit unlimited forward motion of the drum and limited rearward motion thereof.

12. The combination with a check protector, including a printing drum and inking means therefor of a ratchet fixed to the drum; a pawl coacting with said ratchet; a pivot for said pawl arranged to permit the latter to yield when urged by backward motion of said ratchet; and a single spring arranged to urge said pawl into engagement with said ratchet and to oppose said backward motion.

13. In a check protector, the combination 85 of a printing drum provided with a substantially flat printing die for printing a certification legend and a plurality of incising dies adapted to print limiting amounts; a platen having a face arranged to 90 coact with said legend-printing dies, and having a recessed portion adapted to receive said amount-printing dies; a platen bar for the incising dies in said recess; means for rotating said drum to present the 95 various printing faces in printing position; and a mechanism for moving said drum to print upon a sheet held by said platen.

14. In a check protector, the combination 100 of a printing drum provided with a substantially flat printing die for printing a certification legend and a plurality of incising dies adapted to print limiting amounts; a platen having a face arranged to 105 coact with said legend-printing dies, and having a recessed portion adapted to receive said amount-printing dies; a platen bar for the incising dies in said recess; means for rotating said drum to present the various printing faces in printing position; a mechanism 110 for moving said drum to print upon a sheet held by said platen; and a hold-down member yieldingly pressed against said platen and embracing the margin of said recessed portion.

In testimony whereof I have signed my name to this specification.

JOHN J. DUFFIE.
